[57] CLAIM

The ornamental design for a catalyst support for use in a contact lens disinfection unit, as shown.

DESCRIPTION

FIG. 1 is a perspective view of a catalyst support for use in a contact lens disinfection unit, showing our new design;

FIG. 2 is a top plan view thereof;

FIG. 3 is a right side elevational view thereof, the left side elevational view being a mirror image;

FIG. 4 is a front elevational view thereof, the rear elevational view being a mirror image; and

FIG. 5 is a bottom plan view thereof.

FIG. 1

FIG. 2

FIG. 3

FIG. 4

FIG. 5
